UNITED STATES PATENT OFFICE.

CLIFFORD A. ELLIS, OF BAYONNE, NEW JERSEY, ASSIGNEE TO STANDARD OIL COMPANY OF NEW YORK, A CORPORATION OF NEW YORK.

TIRE-EXTINGUISHING APPARATUS.

1,287,928.

Specification of Letters Patent. Patented Dec. 17, 1913.

Application filed January 24, 1910. Serial No. 78,302.

To all whom it may concern:

Be it known that I, Clifford A. Ellis, a citizen of the United States of America, residing at Bayonne, in the county of Hudson and State of New Jersey, have invented new and useful Improvements in Fire-Extinguishing Apparatus, of which the following is a specification.

This invention relates to fire extinguishing apparatus of the class wherein the extinguishing medium is a gas which will not support combustion.

In such systems it has been the practice heretofore to combine certain chemicals at a point remote from the fire zone to produce the fire extinguishing gas, either manually or through the automatic operation of thermostatic controlling means, the gas thus produced being then conducted in the form of foam through long pipes to a suitable point for application to the burning material. Systems of this nature are generally employed in connection with oil tanks or the like, which present horizontal surfaces of burning material at the time of a fire, upon which surfaces the foam may flow and form a blanket which will extinguish the conflagration. These systems are open to several objections which it is my purpose to avoid in my fire extinguishing system.

In the first place, in the foam just mentioned, the fire extinguishing gas is enveloped in a multitude of bubbles. In order to give durability to the foam and enable it to withstand considerable hard usage, licorice or its equivalent is combined with the chemicals which produce the foam, but the foam is nevertheless a delicate substance, and therefore the less handling it receives the greater will be its efficiency. In these early systems, wherein it was necessary to force the foam a considerable distance through small size pipe lines to the fire zone, the results were not satisfactory. Subsequent experiments with lines of large diameter pipe produced more favorable results, although it was discovered that even in this case the volume and efficiency of the foam was destroyed by pressure and friction in flowing through long lines before reaching the fire. Naturally, these systems were not effective in operation and were expensive to install on account of the large diameter of pipe required.

Furthermore, in the systems under consideration numerous methods have been employed for rendering them automatic in operation, but such arrangements have lacked flexibility and, owing to complexity of operation have not proved very reliable. The cost of installation has also made them less practicable.

Briefly stated, it is my primary purpose to improve upon the known systems by providing extremely simple and reliable apparatus for automatically conducting streams of the chemical solutions necessary for the production of the foam from the supply tanks through comparatively long and small size pipes to a point located very close to the fire zone, at which point the chemicals are mixed and the resulting foam is injected through a comparatively short pipe of large cross-sectional area into the tank or other place in which the fire is located, whenever such a fire occurs. The system is auto-pneumatic so as to afford great flexibility and reliability of automatic control and is at the same time arranged for manual control, so that, when properly installed and intelligently maintained, it guarantees practically absolute protection against loss from oil fires.

Further objects of the invention will appear as the following specific description is read in connection with the accompanying drawings, in which:

Fig. 1 is a perspective view of the solution tanks of a unit of the system, showing the pressure equalizing piping, the compressed air supply line and the solution pipes being broken away;

Fig. 2 is a side elevation of the same, showing the manner in which the tanks are embedded in the ground;

Fig. 3 is a side elevation of the mixing and discharging stand-pipe for an oil tank, the latter being shown in section and partly broken away;

Fig. 4 is a side elevation partly in section of the fusible plug for the discharge end of the stand-pipe for a tank, and which serves as a thermostatic release for the solution lines;

Fig. 5 is a perspective view of a hose connection for the solution lines, the latter being broken away;

Fig. 6 is a diagrammatic plan view of a plurality of oil tanks with manifolds and

pipe connections for both automatic and manual controls and the use of two solution supply units;

Fig. 7 is a side elevation, partly in section, of the discharge plug for the manual control connection; and,

Fig. 8 is a side elevation of an oil tank showing both automatic and manual control connections therefor.

Referring to the drawings by numerals, and in particular to Fig. 1, 7 and 8 designate the two solution tanks of a supply unit. These tanks contain the two solutions which, when mixed, will produce the fire extinguishing foam. It is obvious that various combinations of chemical ingredients which will re-act to produce foam containing carbon-dioxide may be employed, but certain ingredients which have been found to be very effective in practice will be specified herein by way of example. The solution for tank 7, for instance, may consist of bi-carbonate of soda, 10%, and water, 90%. The solution for the other tank 8 will then consist of aluminium sulfate, 12%, Greek licorice, 3%, and water, 85%. It is possible to obtain on the market a substance known as "foamite," which is produced from a secondary extract of Greek licorice, and it is found to give very desirable results and is less expensive than glue, glucose and pure licorice, any of which might be used. When this foamite is used as a substitute for licorice, it is added to the bi-carbonate of soda, owing to the preservative qualities of the latter. Therefore, the solution for tank 7 will consist of bi-carbonate of soda, 8%, foamite, 3%, and water, 89%, and accordingly the solution for tank 8 will consist of aluminium sulfate, 11%, and water, 89%. Since the freezing point of either of these solutions is only a few degrees below that of water, proper precautions should be taken to protect them in winter by burying the tanks under ground, or, if it is necessary to keep them above ground, embedding them in manure or other suitable material. When the tanks are sunk into the ground, each will occupy the position shown in Fig. 2 of the drawing.

The two solutions, the ingredients of which have just been specified, are intended to be expelled from the closed steel tanks by air pressure when required for use, as will be described more fully hereinafter. Their combination in a mixing chamber produces a heavy foam having a volume about eight times that of the combined solutions, this increase being due to the carbon dioxide gas that is generated and is enveloped in the bubbles of the foam. Referring again to the proportions of the ingredients specified, it should be stated that the comparison made is on a weight basis.

The size of each of the two tanks, of course, depends entirely upon the amount of

protection required. However, both should at least contain sufficient solutions to extinguish any oil tank afire and protect other oil tanks adjacent thereto. In practice, each gallon of the combined solutions produces approximately eight gallons of foam, which is sufficient to cover one square foot of oil surface. On this basis, two 93' diameter oil tanks will require seven thousand gallons of each solution. In this case, the dimensions of each tank will be 8' diameter by 28' length and will have for substantially two-thirds of its cubical contents the solution contained therein, and for the other one-third of its cubical contents air under gage pressure of 75 lbs. per square inch. This pressure will suffice to force the solutions through the pipe lines, which will be described presently, for a considerable distance. However, by locating the tanks on high ground, gravity will assist the air pressure in this work and it will thus be possible to remove the tanks to a safe distance from the fire zone. By the term "fire zone" is meant the oil tanks to be protected and their immediate vicinity.

The air pressure of 75 lbs. is maintained at all times on the solution tanks by a small air compressor (not shown), if compressed air from a general source is not available. In the drawings, referring again to Fig. 1, the numeral 9 designates a pipe leading from the air compressor to the solution tanks. This pipe line is situated preferably above the level of the tanks and should have two connections for each solution tank. For this purpose, it branches into the pipes 10, which are connected with the tanks 7 and 8 respectively at the tops thereof. A manually operable valve 12 is provided in the pipe 9 and a similar valve 13 is provided in each of the said branch connections. Each valve 13 is positioned at the angle formed in the branch pipe, which latter includes an uppermost horizontal section and lowermost vertical section. A vertical pipe 14 projects through the top wall of each tank and projects into the same to a point near the bottom, so that the lower end of this pipe will be submerged within the liquid at all times. The upper end of this pipe 14 is bent angularly so as to provide a horizontal portion 15 which is connected through the medium of a reducing valve 16 with one of the solution pipes, that for tank 7 being designated by the numeral 17, and that for tank 8 by the numeral 18. Where large manifolds and numerous pipe lines are necessary, each reducing valve should be capable of reducing the air pressure from 75 to 20 lbs. per square inch gage. These valves will thus minimize the loss of air through leakage and will assist thereby in maintaining the requisite air pressure on the solution tanks. A manually operable valve 19 is provided preferably at

the angle formed between the horizontal and vertical portions of each pipe 14. A by-pass 20 is in communication with the vertical and horizontal portions of each pipe 14 and extends around the valve 19. A horizontal branch pipe section 21 containing a check valve 22 connects each by-pass 20 with the horizontal portion of the corresponding pipe 10. Each check valve 22 is adapted to permit flow in the direction of the arrow; in other words, is set against the corresponding solution tank through the pipe 14 to prevent solution passing from one tank into the other. A manually operable valve 23 is provided in each by-pass 20 between the point of connection of the pipe 21 therewith and the point of connection of the by-pass with the vertical portion of the corresponding pipe 14. A similar valve 24 is provided 20 in the by-pass at the opposite side of the point of connection of pipe 21 therewith.

The branch pipes 10 are known as the compensating lines, which are to equalize the pressure in solution lines 17 and 18 which extend to the oil tanks, by means of the check valves 25. These check valves are provided in by-passes 26 which are in communication with the vertical portions of pipes 10, and they are set against the solution tanks as indicated by the arrows. These check valves will allow a small leakage of air to go into the solution lines and will compensate the reduction of the pressure in these lines so that the system will be balanced at all times. This is done to prevent any unequal pressure in the lines from drawing solutions up through pipes 14. A manually operable valve 27 is provided in the vertical portion of each pipe 10 between the points of connection of the by-pass 26 therewith.

Try-cocks 28 project through the tops of the solution tanks into the same to such a depth that they terminate a few inches below the level of the respective solutions contained therein, so that samples may be taken where the density is apt to be low.

A safety valve 29 is connected with the air-filled top portion of each solution tank and is set at 75 lbs. per square inch, its function being to prevent the exertion of a pressure on the solution tanks in excess of that at which the system is operated. Pressure gages 30 are also provided in communication with the top portions of the tanks for use in determining at a glance the air pressure existing within the tanks.

Each solution tank is provided with a manhole 31 provided with a valved vent 32. The use of this vent will be described more fully hereinafter.

The solution pipes 17 and 18 extend directly from the solution tanks to a position preferably at the base of an oil tank to be protected, when there is only one unit of

solution supply. At this point, the pipes 17 and 18 are connected respectively as at 17^a and 18^a with the mixing chamber 33, which latter is in the form of a large T. A stand-pipe 34 rises from this mixing chamber and projects into the tank 35 as at 36 near the top of the same and necessarily above the level of its liquid contents. The inner end of the stand-pipe is closed in an airtight manner by means of a thermal plug, 70 which is preferably in the form of a nipple 37 as shown in detail in Fig. 4 of the drawings. This nipple is closed by means of a metal disk 38, which is supported by a ring 39 of solder which is partially embedded 80 within an annular retaining groove 40 in the nipple. This solder ring has a fusing point of 300 to 325° F. and is tested to twice the working pressure, whereas the disk 38 is constructed of brass or some other comparatively non-fusible metal. The nipple is filled with high melting point wax above the disk 38. Owing to the disposition of the plug thus formed, it will be exposed to the heat of any flame which may occur in the 90 tank. Consequently, heat thus generated will serve to melt the solder ring completely or at least soften the same enough to permit the brass disk to shear the inwardly projecting portion of the said ring away from the 95 nipple as the air pressure within the stand-pipe blows the disk and the mass of wax into the tank through the free end of the nipple.

A try-cock 41 is provided at the bottom of 100 the mixing chamber 33 for use as a tell-tale device at the time of a fire or when testing the apparatus to determine whether solution has been drawn into the lines or if the quality of the foam being delivered is satisfactory.

It is to be understood that the stand-pipe for the automatic control just described need not necessarily be positioned almost entirely on the exterior of the tank as shown in the 110 drawings. Some other obvious disposition or arrangement of the same might be resorted to in practice.

All large oil tanks should at least have one automatic connection and one manual control connection, so that it will be possible to introduce foam into the tank through manual control in case of failure on the part of the thermostatic release device. A convenient arrangement of automatic and manual control connections is shown in Figs. 6 and 8, wherein the two connections for a tank are disposed diametrically opposite to each other. The stand-pipe for the manual control connection, which is indicated by 120 the numeral 42, is identically the same in construction as the stand-pipe 34 of the automatic connection and has a similar mixing chamber 43. In this instance, particularly when the system is employed in connec- 125 130

tion with a battery of tanks as shown particularly in Fig. 6, the solution pipes 17 and 18 are connected with manifolds 17^b and 18^b respectively. These manifolds are closed at 5 their ends and are substantially coextensive with the battery of tanks. When it is desired to protect a series of oil tanks in this manner, the installation is recommended, as an auxiliary solution supply, of a second 10 unit of solution tanks. In this instance, the solution pipes of this auxiliary unit are connected with the manifold as shown in Fig. 6, but are separated by block valves 17ⁱ and 18ⁱ which may be opened when emergency 15 requires and the contents of the auxiliary tanks may then be utilized in the event that the solutions in the other tanks become exhausted.

The stand-pipe 34 of the automatic connection for each tank is connected by means 20 of pipes 17^c and 18^c with the manifolds 17^b and 18^b respectively, whereas the stand-pipe of the manual control connection for each tank is connected in like manner by 25 means of pipes 17^d and 18^d respectively with the said manifolds 17^b and 18^b. Manually operable valves 17^e and 18^e are provided in the pipes 17^d and 18^d for the manual control connection of each tank and are situated preferably adjacent to the manifolds 30 so as to be separated as far as possible from the fire zone. It is desirable also to provide the pipes 17^c and 18^c for each automatic connection with similar valves 17^f and 18^f, 35 which are similarly situated. These valves are, however, normally open, whereas the valves 17^e and 18^e are normally closed.

To prevent the contents of the oil tanks 40 from overflowing into the stand-pipe of the manual control connections, the stand-pipe of each is provided with a nipple 44 at its inner end and this nipple has its free end closed by means of a gasket of sheet lead or like frangible metal which is indicated 45 by the numeral 45 in Fig. 7 of the drawings. It is obvious that this gasket may be secured to the nipple in any convenient manner, but it is illustrated by way of example as being retained by means of a clamping ring 50 46 which embraces the inbent edges of the sheet. This gasket is comparatively thin so that it will be blown out very easily by the air pressure of the system when the corresponding manual control valves are 55 opened.

The manual control valves are intended primarily for use in the case of a fire in one or more tanks when it is desired to protect the contents of adjacent tanks by covering the oil therein with foam, but they 60 may be used to assist the automatic operation in covering the surface of the oil in any particular tank which may be on fire.

In Fig. 5 of the drawings a hose connection is shown. In this instance the solu-

tion line pipes 17 and 18 are tapped and are connected by means of short pipe sections 17^g and 18^g with a T joint 33^a which constitutes a mixing chamber. From this chamber a stand-pipe 34^a leads and is 70 adapted to have a hose 47 connected therewith as at 48. Manually operable valves 17^h and 18^h are provided in the pipe sections 17^g and 18^g respectively and are normally maintained closed. When these valves 75 are opened the solution will be permitted to enter the mixing chamber 33^a and produce foam to be conducted to the indeterminate place where the fire is located through the hose. Hose connections of this sort are 80 preferably provided at a warehouse, wharf or other location where such protection would most likely be required. It has been demonstrated that the foam is very efficient for 85 extinguishing fires in the holds of vessels loaded with case-oil and it follows that satisfactory results would be obtained in fighting oil barge fires with the same. Similar results should be obtained with its use in fighting fires in oil warehouses. 90

The operation of the system will now be described in connection with a single oil tank and a single unit of foam supply. Under working conditions, valves 16, 19, 23 and 13 are open, whereas valves 24, 27, 28, 32 and 41 are closed. While the valves 16 are specified as being open, it is to be understood that they are maintaining a gage pressure of 75 lbs. per square inch within the solution tanks while a reduced pressure 100 of 20 lbs. exists in the solution lines between the reducing valves and the oil tank. The purpose of these reducing valves is three-fold. In the first place, by reducing the pressure they minimize the loss of air 105 through leakage, thereby assisting in maintaining the requisite air pressure on the solution tanks; secondly, they render it possible to fill the system with air very rapidly, since it will require very much less time 110 for a compressor to put the solution line pipes of the system under 20 lbs. pressure than 75 lbs.; and thirdly, they will render the system very rapid in action when the thermal plug, or a manual control, is released, for the system will rid itself of 20 lbs. pressure more readily than it would of 75 lbs. Now, when a fire occurs in the oil tank to be protected, the temperature 115 therein will be raised to the fusing point of the solder which secures the brass closure disk in the fusible plug, whereupon the disk and the high melting point wax will be blown out by the expansive force of the compressed air in the 120 solution line pipes of the system. As soon as the fusible plug is opened, the pressure on the said pipe lines which lead to the oil tank is released, whereupon the highly compressed air within the solution tanks is per- 125 130

50 fitted to force the two solutions upward and outward from their respective tanks through pipes 14 and pipes 17 and 18 to the mixing chamber 38, assuming that there 55 are no manifolds and that the simple form of apparatus disclosed in Figs. 1 to 3 inclusive is in use. In the mixing chamber the solutions will mix and chemical action 60 will result, producing the desired foam containing carbon-dioxide, which will pass through the stand-pipe 34 and the open plug into the top of the oil tank. The 65 foam enters the tank with little velocity and is spread over the blazing surface of the oil without being hurled into the latter and beneath the said surface, where it becomes incapable of having any appreciable effect upon the fire. With the ordinary 70 systems, wherein the foam is produced at a point remote from the oil tank and is conducted through long pipes to the discharge points within the tank, this objectionable 75 high velocity discharge is unavoidable. In the present case, the foam does not mix 80 with the oil, but covers the same in the form of a thick layer or blanket which excludes air from the blazing surfaces and will not support combustion. Consequently, the blaze will be extinguished in a highly 85 efficient manner.

In case the fire is extinguished before the 90 entire charge of the tank is used, the remaining portions of the solutions may be saved for use at another time by closing 95 the angle valves 19, or valves 17° and 18° for the automatic connection or 17° and 18° for the manual connection.

If through some accident to the apparatus 100 before a fire occurs, the entire pressure in both the tanks and solution lines is lost, the system may be operated at the time of the fire by starting the compressor (not shown), in case there is no general supply of compressed air, opening valves 12 and closing 105 valves 23. It is assumed that the system is in working condition, so valves 19 are open. In this way, air will be pumped through both compensating lines into the solution tanks and will force the solutions through 110 the solution lines to the oil tank.

When manifolds, such as those shown 115 in Fig. 6 are employed in connection with a battery of tanks and there are either one or a number of units of supply connected therewith, the solutions will flow from the tanks of any unit to the manifolds and therefrom through the branch pipes to the mixing chamber of the automatic or manual control connection, which has been opened, 120 since all of the other branch pipes are closed.

Provision is made for agitating the solutions in the supply tanks, which should be done once a week, and at that time a test should be made by mixing one pint of one 125 solution with the same quantity taken from

the other solution in a sixteen pint receptacle. The reaction of the chemicals should be instantaneous and the container approximately filled with heavy foam. If this result is not obtained, the chemicals 70 have deteriorated and should be restored to proper strength by the addition of sufficient ingredients. For the purpose of this test, the required quantity of each solution is drawn from the tanks containing the same 75 through the try-cek 28.

When practicable, at least annually, an inspection should be made of the tanks and if there is evidence of corrosion in one tank and none in the other, a cleansing of both is 80 recommended. When recharging the tanks, the solution that caused the corrosion should be placed in the other tank. This transposition of the solutions will not affect the operation of the system in any way and will 85 prevent one tank from becoming unserviceable before the other.

Agitation of the solution is effected by closing valves 13 and 19, and opening valves 12, 23 and 32 so that air may blow through 90 pipe 9, the horizontal portions of pipes 10, pipe 21, portions by-passes 20, and the vertical portions of pipes 14 into the solution tanks at the bottoms thereof. The air will then pass upwardly through the 95 solutions and out of the manholes and valves 32 to the atmosphere with great force, thus causing violent agitation of the solutions in the tanks.

The by-passes around valves 19 are introduced to prevent any solution from rising in the pipes 14 when the pressure is built up in the tanks and transferred to the solution lines after agitation. The restoration of the pressure is accomplished by first 105 opening valves 13 so that air may pass through the compensating lines 10 into the tops of the tanks. The air is pumped into the tanks in this manner until the gage pressure registers 75 lbs., at which time the 110 valves 23 are closed and valves 24 are opened. The reducing valves 16 having been left open will allow the equalization of the entire system before the valves 19 and 23 are opened and valves 24 are closed to 115 place the system in working condition again. Then valve 12 is closed and valves 27 are operated momentarily to equalize the pressure above and below check-valves 25. Finally, valves 27 are closed. 120

Numerous advantages of the system have 125 been pointed out and others have undoubtedly become apparent to the reader as the specification was read in connection with the accompanying drawings, but the salient features will be enumerated by way of emphasis. In the first place, the foam-producing ingredients are stored at a considerable distance from the fire zone and in such a manner as to preclude any deteriorating in- 130

fluences upon the ingredients due to atmospheric or temperature conditions. Then, the stored ingredients are maintained under a static pressure sufficient to deliver the 5 same instantly to the mixing point adjacent to the fire zone when released either manually or automatically. Since the ingredients are under pressure when they are mixed, they will commingle instantaneously 10 and will insure an accelerated generation of foam and a discharge of the same more rapid than the discharge of foam by its own expansion, but not so rapid as to hurl it into the burning oil, which has been pointed out 15 heretofore as being objectionable. Since the foam is produced at a point adjacent to the fire zone, its delivery will be prompt during chemical reaction, so there will be no long 20 and foam-destroying passage through long pipes, spray nozzles, or other restricting ducts. Consequently, when a fire occurs, a tenacious and lingering, foaming mass in a state of chemical reaction and violent ebullition will be discharged suddenly onto the 25 burning surfaces and will possess both cooling and fire extinguishing properties to a very high degree. Another important feature resides in the fact that, with the length and size of conducting pipes of a particular 30 apparatus in mind, the time of delivery on release of the static pressure may be regulated by increasing or decreasing the degree of this pressure when the system is initially placed in working condition. If it is found 35 to be desirable after the apparatus has been installed to increase the length of or ramify the conducting pipes of the system to accommodate the apparatus to an increased 40 number of oil tanks or the like, the static pressure may be adjusted correspondingly in a manner which should be readily understood.

Having thus described the invention, what it is desired to claim and to secure by Letters-Patent of the United States is:

1. A fire-extinguishing apparatus comprising a storage receptacle for fire-extinguishing fluid, a conducting pipe leading from the receptacle, controlling means for 50 the conducting pipe adapted normally to close the same at the discharge end, a reducing-valve provided in the pipe near the receptacle and adapted normally to maintain a reduced pressure at the side of the 55 same opposite to the receptacle, a supply pipe for compressed fluid connected with the receptacle behind the fluid contained therein and with the conducting pipe at a point located between the reducing valve and the 60 receptacle, and means for maintaining a pressure in the supply pipe on the receptacle sufficient to force the fire-extinguishing fluid through the conducting pipe when the pressure in the latter in advance of the 65 said valve is released.

2. A fire-extinguishing apparatus comprising a plurality of storage receptacles for separately stored foam-producing ingredients, a mixing chamber, separate conducting pipes for the said ingredients leading from 70 the respective storage receptacles to the mixing chamber, a discharge pipe leading from the said chamber, controlling means for the discharge pipe adapted normally to close the same, means for maintaining a static 75 pressure in each storage receptacle behind the charge of ingredients contained therein sufficient to force it through the conducting pipe when released, for applying a pressure within the conducting pipe for each receptacle 80 immediately in advance of the latter sufficient to counter-balance the pressure behind its charge of ingredients and for maintaining a reduced pressure throughout the rest of each conducting pipe while the said 85 discharge pipe is closed.

3. A fire-extinguishing apparatus comprising a plurality of storage receptacles for separately stored foam-producing ingredients a mixing chamber, separate conducting pipes for the said ingredients leading from the respective storage receptacles to the mixing chamber, a discharge pipe leading from the said chamber, controlling means for the discharge pipe adapted normally to close the same, means for maintaining a static pressure in each storage receptacle behind the charge of ingredients 90 contained therein sufficient to force it through the conducting pipe when released, 95 for applying a pressure within the conducting pipe for each receptacle immediately in advance of the latter sufficient to counter-balance the pressure behind the charge of ingredients and for maintaining a reduced 100 pressure throughout the rest of the conducting pipe when the controlling means therefor is closed, the means for maintaining said static pressure in each storage receptacle including relative to each receptacle in addition to said conducting pipe, a second pipe 105 leading to another part of the receptacle than said conducting pipe, a branch pipe connecting said two pipes, and a reducing valve in said discharge pipe.

4. A fire-extinguishing apparatus of the class described comprising a pair of storage receptacles for separately stored foam-producing ingredients situated remote from the fire zone, a mixing chamber disposed close 110 to the fire zone, separate conducting pipes for the said ingredients leading from the respective storage receptacles to the mixing chamber, a discharge pipe leading from the said chamber, controlling means for the 115 discharge adapted normally to close the same, the said storage receptacles being provided with compressed fluid adapted to place the ingredients therein under static pressure sufficient to propel the same 120

through the conducting pipes when released by the said controlling means, pressure reducing valves provided in the said conducting pipes in suitable proximity to the storage receptacles for retaining the pressure in the receptacles and at the same time maintaining a pressure of lower degree in the portions of the said pipes which lead from the reducing valves to the mixing chamber, 10 a manually operable valve provided in each of the said conducting pipes between the reducing valve thereof and the corresponding storage receptacle, by-pass provided in each conducting pipe to extend around the manually operable valve, two manually operable valves provided in each of the said by-passes, a supply pipe leading from a source of compressed fluid, a valve provided in the supply pipe, branch pipes leading 20 from the supply pipe to the tops of the storage receptacles, connecting pipes leading from the said branch pipes to the said by-passes of the respective conducting pipes and being connected with the by-passes at points situated between the two valves in each instance, the conducting pipes being in communication with the storage receptacles substantially at the bottoms thereof, check-valves provided in the said connecting 25 pipes and being set against the conducting pipes, a manually operable valve provided in each of the said branch pipes between the point of connection of the corresponding connecting pipe therewith and the corresponding storage receptacle, a second manually operable valve provided in each 30 branch pipe between its first-mentioned valve and the corresponding storage receptacle, a by-pass provided in each branch pipe to extend around the second valve 40 therein, a check-valve provided in each of the last-mentioned by-passes and being set against the storage receptacle, and a valved vent provided at the top of each receptacle. 45

5. A fire-extinguishing apparatus comprising a storage receptacle for fire-extinguishing fluid, a conducting pipe leading from the receptacle, controlling means for the conducting pipe adapted normally to close the same at the discharge end, means 50 for maintaining a static pressure in the receptacle behind the said fluid sufficient to force it through the conducting pipe when released for applying a pressure within the conducting pipe immediately in advance of 55 the said receptacle sufficient to counterbalance the pressure behind its fluid contents and for maintaining a reduced pressure throughout the rest of the pipe while its discharge end is closed, the means last mentioned including a pipe leading from a source of compressed fluid to the receptacle and a continuously open conduit between the pipe last-mentioned and said conducting pipe. 60
